J. L. FERRIN

CLEANING TOOL

Filed Oct. 17, 1925

Inventor

Joseph L. Ferrin

By Right from Quincy May

Atty.

UNITED STATES PATENT OFFICE.

JOSEPH L. FERRIN, OF LAWRENCE, MASSACHUSETTS.

CLEANING TOOL.

Application filed October 17, 1925. Serial No. 62,977.

The object of this invention is to provide a cleaning tool adapted to apply water to a surface carrying caked mud, to soften the same and to remove the softened mud by a scraping action; which may be followed by a rinsing or washing action, the tool being intended for use in cleaning surfaces of mud guards of motor vehicles, although it may be used on other surfaces.

10 Of the accompanying drawings forming a part of this specification,—

Figure 1 is a side view of a cleaning tool embodying the invention.

15 Figure 2 is a section on line 2—2 of Figure 1.

Figure 3 is a fragmentary sectional view, showing a portion of the handle, the scraping blade being removed.

20 Figure 4 is a fragmentary perspective view, showing a portion of the scraping blade.

25 Figure 5 is a view similar to a portion of Figure 2, showing one of the passages constituting the two-part outlet, closed by a valve.

Figure 6 is a section on line 6—6 of Figure 1.

Figure 7 is a section on line 7—7 of Figure 3.

30 The same reference characters indicate the same parts in all of the figures.

12 designates a handle formed to be grasped by one of the operator's hands. The handle is provided with a longitudinal bore 13, at the outer end of which is a hose-coupling member 14, whereby the handle may be connected with a complementary coupling member on a water-conducting hose.

40 15 designates a scraping blade, preferably flat sided and decreasing in width from its outer to its inner end. To one end of the blade is fixed a shank 16, inserted in the opposite end portion of the bore 13. Said shank and the bore form an outlet communicating with the bore and adapted to project water besides the blade, to soften caked mud on a surface to be cleaned by the tool. The blade is preferably detachably secured to the handle, and the construction whereby the blade is secured to the handle and the outlet is formed, is preferably as next described.

The inner end portion of the handle is

provided at opposite sides of the bore with 55 transverse slots 18 intersecting the inner end portion of the bore and extending therefrom to opposite sides of the handle, as shown by Figure 7, the slots being narrower than the bore, as shown by Figure 3. 60

The shank 16 is formed to closely fit the slots, and to extend from slot to slot across the bore 13. The shank is secured in the slots by suitable means, such as screws 19, inserted in orifices 20 in the shank, and in 65 coinciding orifices in the handle, at opposite sides of the slots 18; the shank extending across the bore, as shown by Figure 6.

70 Portions of the opposed sides of the shank 16 and of the bore 13 are spaced apart and form an outlet, adapted to project water besides the blade. Preferably the outlet includes two passages 21 (Figures 2, 5 and 6) at opposite sides of the shank, arranged to 75 project two jets 22 of water, as indicated by Figure 2, and cause contact of said jets with the outer end portion of the blade.

75 In this instance the inner end portion of the bore 13 is square in cross section, so that 80 it has flat sides forming sides of the passages 21. The thickness of the shank is less than the width of the square portion of the bore, so that the sides of the shank are spaced from the adjacent sides of the bore, as shown 85 by Figure 6, to form the passages 21.

80 The walls of the bore 13 which intersect the slots 18, are tapered as indicated at 13^a Figure 7, so that the passages 21 are fan-shaped and are adapted to deliver fan-shaped jets, as indicated by Figure 1.

85 It will now be seen that a mud-guard surface coated with caked mud, may be quickly cleaned by applying the blade thereto and causing water to flow through the 90 handle. The water and the outer end of the blade may simultaneously attack the mud. After the mud has been removed, the surface may be washed by water projected from the handle. It is obvious that the 100 tool may be used for other purposes.

95 A valve may be provided to close one of the passages 21, if desired, and may be constructed and operated in any suitable manner. In this instance, the valve is a block 105 25, which may be of compressible material, and is movable by an adjusting screw 27 in a recess 26, formed in the handle and com-

municating with the bore 13. When the valve is forced inward, it closes one of the passages 21, as shown by Figure 5.

I claim:

- 5 1. A cleaning tool comprising a handle and a scraping blade of hard material fixed to and projecting from one end thereof and having a scraping edge at its outer end, the handle being provided with a water-conducting bore, a hose-coupling member at one end of the bore, and an outlet at the opposite end of the bore, located adjacent the inner end of the blade, and adapted to project a jet of water beside the blade to 15 the scraping edge thereof.
- 10 2. A cleaning tool comprising a handle and a scraping blade fixed to and projecting from one end thereof, the handle being provided with a water-conducting bore, a hose-coupling member at one end of the bore, and an outlet at the opposite end of the bore, adapted to project a jet of water beside the blade to the outer end thereof, so that the jet may impinge on a surface being 20 cleaned, the outlet being composed of two portions, one located at one side, and the other at the opposite side of the blade, and
- 25

adapted to project two jets of water beside the blade to the outer end thereof.

3. A cleaning tool comprising a handle 30 having a longitudinal water-conducting bore, a hose-coupling member at one end of the bore, and a scraper having a shank inserted in the opposite end portion of the bore, said shank and bore portion forming 35 an outlet composed of two portions and adapted to project water at opposite sides of the scraper, the tool also comprising a valve adapted to close one of said outlet portions.

4. A cleaning tool comprising a handle having a longitudinal water-conducting bore, a hose-coupling member at one end of the bore, and transverse slots intersecting 45 one end portion of the bore, a scraper having a shank inserted in said slots, and extending across the said end portion, and means securing the shank to the handle, said shank and bore portion forming an 50 outlet adapted to project water beside the scraper.

In testimony whereof I have affixed my signature.

JOSEPH L. FERRIN.
